George Nicholas Mas, Washington, D.C., assignor to Frank du Mas

Application March 21, 1957, Serial No. 45,380

Term of patent 14 years

(Cl. D58—8)

FIG. 2.

FIG. 1.

Fig. 1 is an elevational view, showing my new bottle design and;

The side of the bottle not shown is the same as the side shown.

The characteristic features of my design for the bottle disclosed reside in the surface ornamentation at the shoulder portion and the teardrop like elements disposed on the body portion of the bottle having the configurations shown.

I claim:

The ornamental design for a bottle, as shown and described.
